DESIGN FOR A MOTOR VEHICLE

Neil P. Larsen and Herman J. Troche,
Cleveland, Ohio

Application March 25, 1939, Serial No. 83,825

Term of patent 14 years

To all whom it may concern:

Be it known that we, Neil P. Larsen and Herman J. Troche, citizens of the United States, each residing at Cleveland, in the county of Cuyahoga and State of Ohio, have invented a new, original, and ornamental Design for a Motor Vehicle, of which the following is a specification, reference being had to the accompanying drawing, forming a part thereof.

In the drawing, Fig. 1 is a perspective view of

a motor vehicle embodying our design; Fig. 2 is a rear view of the vehicle; Fig. 3 is a side elevation illustrating the side opposite that shown in Fig. 1. The dominant features of our design reside in the portions shown in full lines.

We claim:

The ornamental design for a motor vehicle, substantially as shown and described.

NEIL P. LARSEN.
HERMAN J. TROCHE.
